UNITED STATES PATENT OFFICE.

WILLIAM L. DEMING, OF SALEM, OHIO.

CASH-RECORDING DEVICE.

1,299,689.

Specification of Letters Patent.

Patented Apr. 8, 1919.

Application filed November 3, 1916. Serial No. 129,325.

To all whom it may concern:

Be it known that I, WILLIAM L. DEMING, a citizen of the United States, residing at Salem, in the county of Columbiana and State of Ohio, have invented a certain new and useful Improvement in Cash-Recording Devices, of which the following is a full, clear, and exact description, reference being had to the accompanying drawings.

10 This invention relates to devices for recording sales or similar transactions and is of that general type wherein the transaction is noted in writing on a suitable record strip. An important object of this invention is to 15 provide a stamping device arranged to operate on a record strip and connected with the record strip by suitable mechanism for feeding the strip consequent upon the operation of such stamping device. Another object is to so arrange the recording device that two strips of paper may be used, one of which is a customer's record directly receiving the notation of the sale and is stamped and severed from the remaining portion of 20 the strip and handed to the customer, while the same writing is transmitted through such strip to the "house record" strip beneath, which is retained in the machine. Still another object is to so arrange the feeding 25 devices that the movement of the stamping means may serve to feed strips in proper relation to the movement of the stamping device, so that the record portion of one strip is delivered to a position where it may 30 be severed from the strip, while the other strip is so moved as to be inaccessible, thus preventing fraudulent alteration of records.

More specific objects are to so construct the feeding devices that they may be simple, efficient and so connected with the stamp carrying means that the stamping device may be readily removed from the remaining portion of the register.

Referring to the drawings, Figure 1 is a 45 plan view of my recording device; Fig. 2 is a section of the same taken at the near side of the record strips and their rolls; Fig. 3 is a similar section taken through the middle portion of the record strips and 50 showing the stamp in its stamping position; Fig. 4 is a similar section showing the stamping device and upper record strip removed; and Fig. 5 is a front elevation of

the device; Fig. 6 is a detail showing the under side of the customer's record strip. 55

While this device is adapted for use with any kind of a support it is frequently useful with a cash drawer for containing the cash recorded. For example, satisfactory results are obtained by mounting this device 60 on the cover of a cash drawer of the type shown, described and claimed in my prior Patent No. 1,092,564, issued April 7, 1914. For the purposes of the present invention I have shown in the drawings a flat support 65 which may be associated with any device with which this invention may be particularly useful in practical operation. In the drawings this support is indicated at 10 and on this support is mounted a flat metal plate 70 12 having upwardly turned integral side portions 14, providing pivotal bearings 15 for a swinging bail-shaped lever 16 pivotally carrying a stamp support 17, to the under side of which is preferably removably 75 secured a rubber receipting stamp indicated at 20.

The stamp carrier is shown as comprising a bridge portion 21 integral with upwardly turned ends 22 pivoted to the side arms of 80 the actuating lever 16 at 24. Beneath the bridge portion 21 is removably secured a stamp base 25 to which the rubber stamp 20 is permanently secured, and the base portion is shown as provided with spring clips 85 26 adapted to embrace the sides of the bridge 21 to hold the stamp in position.

At 28 is shown a suitable inking pad for the stamp, horizontally disposed above the plate 12 and supported at its ends, the stamp 90 20 being adapted to rest on this pad as shown in Fig. 2 or be moved to the printing position shown in Fig. 3. The means for keeping the stamp 20 with its printing surface in a horizontal position at all times preferably comprises arms 30 and 31. Each of these arms is pivoted at one end to the side members 14 and at the other end to the end members 22 of the stamp carrier. For purposes of rigidity the pivot points of the arm 95 30 are arranged vertically beneath the points 15 and 24 of the bail, while the pivot points of the arm 31 are laterally disposed with relation to 15 and 24, as shown particularly in Fig. 2.

At 35 is shown a roller having large 100 105

105

flanges 36 at its ends and carried on bearing arms 37 extending upwardly and rearwardly from the side wings 14 of the plate 12. The arms 37 embrace trunnions 38 on the end of the roller 35 and are adapted to be sprung outwardly to permit the ready removal of the roller for replenishing the supply of paper indicated at 40 and comprising the customer's record strip. When in operation 10 the strip 40 passes downwardly from the roller 35 beneath a guide roller 42, forwardly beneath the stamp 28 and across the plate 12 to a point where it may be written upon.

15 Above the plate 12 is a transverse metal strip 44 attached at its ends to the plate 12, at each side of the record strip, and carrying legends forming column headings for columns printed on the record strip. Forward of this bridge is a second bridge member or cover plate 45 also attached at its opposite ends to the plate 12 and rising slightly and extending across the record strip. This member 45 is cut away at 46 leaving a limited area of the record strip 40 exposed for receiving the stamp 20.

Beneath the support 10 and carried by suitable brackets 48 is a shaft 49 on which are rigidly mounted a pair of separated 30 wheels 50, preferably each provided with rubber on the periphery, and extending upwardly through an opening in the plate 12. These rollers press against small coating rollers 52, mounted above the plate on suitable brackets 53. The edges of the record strip 40 pass between and are pinched by the rollers of each set, whereby the rotation of the rollers 50 may effect the feeding of the strip 40. To cause such feeding consequent 35 upon the movement of the stamp and in proper relation thereto, I have shown an upwardly extending arm 55 on the link 31 (Fig. 2) pivotally secured to a downwardly extending link 56 which is in turn pivoted 40 at its lower end to a loose crank arm 58 on the shaft 49. This arm carries a pawl 60 adapted to engage a ratchet wheel 62 rigid with the shaft 49. A weighted arm 63 extends through the pivot joint 57 and is attached to the pawl 60 and so positioned that as the arm 58 swings downwardly and is returned to the position shown in Fig. 2 the weight of this arm 63 tends at all times to urge the pawl 60 into engagement with the 45 ratchet wheel 62. An inspection of these parts in position shown in Fig. 4 will make this operation clear.

The operation of the parts thus far described is as follows: A customer having 60 made a purchase or paid a bill, this is noted in writing on the record strip 40 just in front of the bridge 44 and the amount of the transaction is noted in the proper column at the right of the record strip. The bail 16 65 is then grasped by the operator and swung

forwardly from the position shown in Fig. 2 to that shown in Fig. 3, bringing the stamp 20 onto the record strip in the space just in front of (or with relation to the strip, below) the written notation. This forward 70 movement swings the arm 55 downwardly causing the arm 58 to swing, in an arc of approximately a third of a revolution, to position at the lower side of the ratchet wheel 62. On the return movement of the 75 bail 16 the link 56 is drawn upwardly moving the arm 58 and the ratchet 62 in an arc and correspondingly rotating the portion carrying the written and stamped record 80 forwardly to the position shown in Figs. 1 and 2. Here it may be grasped and severed from the remaining portion of the strip by tearing along the beveled edge 47 of the bridge 45. This severed portion comprises 85 a customer's receipt, and the stamp preferably carries the name of the firm with the word "Paid", with the date and any other suitable notations, such for example as the statement that the customer's receipts are good for two per cent. of their value when 90 returned in a quantity as representing a given amount.

It is desirable to provide at the same time a permanent "house record" of each transaction which I accomplish by providing a 95 carbon duplicating surface for the greater portion of the width of the strip 40, on its under side, as indicated at C in Fig. 6. This carbon surface preferably stops short of each side leaving a boarder B where the 100 wheels 50 and 52 engage the strip for feeding it. As the record of the sale is made the carbon of this surface is adapted to be transferred to make a written record on the "house record" strip, indicated at 105 70, which is exposed to the carbon only beneath the writing opening. The strip 70 is led upwardly over a bridge member 72 and downwardly at the other side of the same from a supply roll 74 to a receiving and feeding 110 roll 75. This bridge is indicated in Figs. 3 and 4 and is mounted on the support 10 to fit into a correspondingly shaped opening 115 in the plate 12, leaving spaces between the bridge and plate, allowing free movement of the strip.

The roll 75 is shown as wound onto a receiving roller 76, provided with a hinged flap 78 carrying pins 79 adapted to pierce the end of the record strip and clamp the 120 same for starting the roll. At the end of this roller 76 is provided a ratchet wheel 79 adapted to be acted upon by an arm 80 carrying a tooth 81 coating with the teeth of the ratchet 79. This arm 81 is pivotally connected to an arm 83 shown as integral with the link 31, and the tooth 81 is urged into engagement with the teeth of the ratchet wheel by the weight of the arm 80.

It will be seen that on the first part of 130

the forward movement of the stamp, the roller 76 will be rotated, moving the written record last made on the strip 70 rearwardly a short distance bringing this writing off 5 from the bridge 72 to a position just to the rear thereof and presenting a blank space to the writing position. The tooth 81 passes out of engagement with the ratchet 79, and the smooth portion of the arm passes idly 10 over the same for the remaining portion of the movement of the arms 31 and actuating lever 16. On the return movement of the stamp, to the position in Figs. 1 and 2, the tooth 81 passes idly over the teeth of the 15 ratchet 79, and the notation on the strip 70 remains in its protected position, while the customer's receipt is delivered.

When the support 10 forms a corner or other part of a cash drawer it is desirable to 20 provide for removing the stamping device, leaving only the flat surface of the support, permitting the drawer to be moved into its receptacle. In the embodiment shown the support 10 is provided with a large opening 25 in which the lower record rolls and the wheels 50 etc. are positioned, while a suitable metal trough-shaped member 85 is mounted in this opening to carry the supply roll 74. The plate 12 is preferably adapted 30 to be locked onto the support 10 to prevent access to the permanent record strip, thus insuring against fraudulent alteration of the records thereof. A convenient means for accomplishing this locking is to provide 35 hooks 86 adapted to engage beneath the support 10 at the rear of the opening therein and provide a lock 88 having a bolt 89 adapted to enter a receptacle 90 formed by the metal of the roll holder 85. A keyhole 40 through the plates 45 and 12 is provided at 92 for operating this lock 88. This lock may be placed in the middle, or one may be used at either corner.

The link 56 is shown as secured to the arm 45 55 by a thumb nut 95, Fig. 5, whereby this link may be disconnected from the arm of the link 31 permitting the stamping device, plate 12 and parts carried thereby to be left freed from the support, while the link 56 50 merely drops to the position shown in Fig. 4, which figure shows the support with the stamping mechanism removed.

From the foregoing description it will be seen that this device is useful for recording 55 sales, payments and like transactions in many lines of business. The invention has been found particularly useful when associated with cash receptacles for containing the cash recorded on the record strip, but 60 this method of recording and stamping is useful in connection with transactions of various natures. For example, bank deposit slips may be written and stamped, as described in the operation of this device, the 65 severed slip being handed to the patron and

the permanent or "house record" containing a record of the day's transactions retained on the permanent roll.

Having thus described my invention, what I claim is:

1. In a recording device, the combination 70 of a support for a record strip, a guideway for the strip on the support, a writing window where a portion of the strip is exposed, a stamp adapted to print on said strip through said window, a carrier for the stamp, an inking pad, said stamp adapted to be moved from the pad to the strip and returned, and means to feed the strip consequent upon the movement of the stamp. 75

2. The combination of means for holding 80 in wound up form two superposed record strips having transfer material between them and one narrower than the other, means for supporting said strips and having a writing support and an opening for writing, means for feeding the narrower strip to carry the transferred writing just past the support and to a protected position, and means including a pair of separated feed rollers 85 respectively beyond the edges of the narrower strip for feeding the wider strip to deliver the written portion thereof, mechanism for stamping an imprint on an exposed portion 90 of the strip, the feeding means being actuated by the stamping mechanism. 95

3. In a recording device, the combination 100 of means for carrying a customer's record strip and a house record strip, a support over which both of said strips are led and at which they may receive a written record, one of said strips being wider than the other, a stamping device acting on one of said strips, and means for feeding one of said strips with relation to the other, said means engaging 105 the wider strip at its edges outside of the other strip.

4. In a recording device, the combination 110 of means for carrying a customer's record strip and a house record strip, a support over which both of said strips are led and at which they may receive a written record, one of said strips being wider than the other, a stamp acting on one of said strips, an inking pad, means for moving the stamp from the pad to the strip, and means for feeding said strips different distances consequent upon such stamping movement, said means engaging 115 the wider strip at its edges outside of the other strip. 120

5. In a recording device, the combination 125 with means for carrying a customer's record strip and a house record strip beneath the first mentioned strip, of a supply roller and a guide therefor, said guide providing a writing space, means transferring writing from the first mentioned strip to the second mentioned strip, a pair of separated rollers engaging the edges of the first mentioned strip, said house record strip passing be- 130

tween said rollers, a receiving roller for the house record strip, a movable stamp for printing on one of said strips, means actuated by the movement of the stamp for actuating the separated rollers and receiving roller for advancing said strips with relation to the writing space.

6. In a recording device, the combination with means for carrying a record strip having a record-transferring surface on one side, of a movable stamp adapted to print on the strip, a permanent record strip beneath the first mentioned strip, and means actuated by the movement of the stamp for advancing both strips, one of said strips being wider than the other and said means including rolls engaging the wider strip at its edges.

7. In a recording device, the combination with means for carrying a customer's record strip and a house strip, guideways for each of said strips having writing openings, a stamp, an inking pad therefor, means for moving the stamp from the inking pad to one of said strips and returning it thereto, means whereby writing on the record strip is also transferred to the house strip, means for advancing both of said strips to move the record portion away from the writing openings, the means being actuated by the movement of the stamp.

8. In a recording device, the combination of a guideway for a record strip, a supply roll at one end of said guideway, a support for the roll and guideway, the guideway having a writing opening and exposing the surface of the strip adjacent the writing opening, an inking pad adjacent the guideway, a stamp, parallel arms carrying said stamp for presenting it to the pad and record strip adjacent the writing opening, a narrower record strip beneath the record strip, a receiving roller therefor, said strip

passing over the writing support, means for transferring writing made on the upper strip to the lower strip, and means connected with the parallel arms for actuating said receiving roll on the first part of the printing movement, the rollers engaging the edges of the first mentioned strip and actuated by said parallel arms to advance the strip engaged thereby on the return movement of the stamp.

9. In a recording device, the combination of means for carrying a record strip and a surmounting customer's strip, an inking pad, a traveling stamp adapted to travel from the inking pad to the customer's strip and back, means for transferring writing from the customer's strip to the record strip, and means consequent upon the movement of the stamp for feeding both strips.

10. In a device of the character described, the combination of means for guiding a record strip, a support for the same, means for guiding a customer's strip over the record strip, a casing having a visible opening over the customer's strip at a point where it is above the record strip and both above the support, whereby writing at this point on the customer's strip may be transferred to the record strip, the casing having an adjacent opening, means for supporting the customer's strip independent of the record strip beneath such portion of the opening, a hand stamp adapted to engage the customer's strip in the last mentioned region, an inking pad, mechanism for moving the hand stamp from the inking pad to the customer's strip and back to the pad, and means for feeding both strips consequent upon such movement of the hand stamp.

In testimony whereof, I hereunto affix my signature.

WILLIAM L. DEMING.
